(57) **CLAIM**

The ornamental design for the handle for tongue cleaning device, as shown and described.

DESCRIPTION

FIG. 1 is a top plan view of the handle for tongue cleaning device.

FIG. 2 is a side elevation view of FIG. 1;

FIG. 3 is a front elevation view of FIG. 1;

FIG. 4 is a top plan view of a second embodiment of the handle for tongue cleaning device.

FIG. 5 is a side elevation view of FIG. 4; and,

FIG. 6 is a front elevation view of FIG. 4.

The dashed lines show an exemplary application for the handle for tongue cleaning device and form no part of the claimed design.
